[57] CLAIM

The ornamental design for a ice scoop handle, as shown and described.

DESCRIPTION

FIG. 1 is a top plan view of the ice scoop handle of the present invention;

FIG. 2 is a bottom plan view of the ice scoop handle of FIG. 1;

FIG. 3 is a right side elevational view of the ice scoop handle of FIG. 1;

FIG. 4 is a left side elevational view of the ice scoop handle of FIG. 1;

FIG. 5 is a front elevational view of the ice scoop handle of FIG. 1; and,

FIG. 6 is a back elevational view of the ice scoop handle of FIG. 1.

The broken lines showing of an ice scoop in FIGS. 1-6 is for illustrative purposes only and forms no part of the claimed invention.
